LIQUID GAUGE WITH MULTIPLE SIDE SIGHT OPENINGS

Gus J. Lukas and Floyd J. Bydalek, Manitowoc, Wis., assignors to Lube Devices, Inc., Manitowoc, Wis., a corporation of Wisconsin

Filed Mar. 27, 1968, Ser. No. 11,156

Term of patent 14 years

Int. Cl. D10—08

U.S. Cl. D52—6

FIG. 1 is a front perspective view showing the design of a liquid gauge with multiple side sight openings.

FIG. 2 is a rear perspective view showing the design.

FIG. 3 is a front elevation showing the design.

FIG. 4 is a side elevation showing the design.

FIG. 5 is a cross section taken along the line 5—5 of FIG. 3.

The essential features of the design are shown in full lines.

We claim:

The ornamental design for a liquid gauge with multiple side sight openings, as shown and described.
